UNITED STATES PATENT OFFICE.

JOHN BORNER, OF RAHWAY, NEW JERSEY.

APPARATUS FOR IMPREGNATING WOOD.

SPECIFICATION forming part of Letters Patent No. 703,522, dated July 1, 1902.

Application filed January 17, 1902. Serial No. 90,140. (No model.)

To all whom it may concern:

Be it known that I, JOHN BORNER, a subject of the King of Great Britain, residing at Rahway, in the county of Union and State 5 of New Jersey, have invented certain new and useful Improvements in Apparatus for Impregnating Wood; and I do hereby declare the following to be a full, clear, and exact description of the invention, such as will enable 10 others skilled in the art to which it appertains to make and use the same, reference being had to the accompanying drawings, and to numerals of reference marked thereon, which form a part of this specification.

15 The present invention has reference to a novel construction and arrangement of apparatus or device for the treatment of wood, preferably in the form of logs or beams, with a mixture having excessive hardening and 20 fireproofing properties, the arrangement and construction of the parts of the apparatus being such that the fluid mixture is forcibly driven into one end of the log or beam, so as to thoroughly permeate the log or beam longitudinally with the long grain of the wood, whereby the log or beam is rendered resistible or tenacious to pressure and the wood can be subjected to the action of a die or 25 dies bearing a design and then under pressure 30 sure can be provided with any suitable ornamentation in perfect imitation of hand-carving without in the least distorting or tearing the fiber of the wood.

The principal object of this invention, therefore, is to provide a novel and simple as well 35 as a durable apparatus of the character and for the purposes above set forth in which a log or beam can be subjected to the action of the fluid mixture and the log or beam thoroughly impregnated with the mixture without the necessity of exhausting all the air from the apparatus during the process of 40 treating the wood; as heretofore, and thereby greatly simplifying the construction of the 45 apparatus, as well as reducing the various steps in the process of handling and treating the wood, and whereby also, finally, the cost of manufacture is reduced to a minimum.

The apparatus forming the subject-matter 50 of the present application is also applicable for the treatment of wood in the form of boards, slabs, blocks, or any other shape

with a fireproofing mixture or other fluid mixture for rendering the wood waterproof and resistible or tenacious to the pressure 55 from dies.

The invention therefore consists in the novel apparatus for the treatment of wood or other material, but preferably logs or beams, in which the impregnating fluid is forced in 60 the one end of the piece to be treated by pressure throughout the entire piece longitudinally and parallel with the long grain of the piece.

The invention consists, furthermore, in 65 such novel arrangements and combinations of the various devices and parts thereof for the purpose of impregnating the log or beam with a mixture which renders it resistible and tenacious to pressure and also fireproof 70 as well as waterproof, all of which will be more fully described in the following specification and then finally embodied in the clauses of the claim, which form a part thereof.

The invention is clearly illustrated in the 75 accompanying sheets of drawings, in which—

Figure 1 is a side elevation of the apparatus for treating the wood, and Fig. 2 is a plan view of the same. Fig. 2^A is a longitudinal vertical section of the main tank or boiler of 80 the apparatus with the remaining parts of the apparatus represented in side elevation, the said view also illustrating a portion of a log in its position in the apparatus for treatment. Fig. 3 is a longitudinal vertical section 85 of all the main parts of the apparatus, said section being taken on line 3 3 in Fig. 2 of the drawings, but the log or beam being merely indicated in dotted outline. Fig. 4 is a rear end view of the main tank or boiler. Fig. 5 90 is a vertical cross-section of the apparatus, said section being taken on line 5 5 in said Fig. 3 of the drawings looking in the direction of the arrow x; and Fig. 6 is a longitudinal vertical section of a spring-actuated 95 buffer which is employed in connection with the main tank or boiler.

Similar characters of reference are employed in all of the said above-described views to indicate corresponding parts.

In the said drawings the reference character 1 indicates a suitably-constructed tank or boiler, which is preferably of a cylindrical configuration, as represented, the same being

made with a closed end 2 at the front and with an end 3 at the rear, the said rear end, however, being made with a suitable opening 4, substantially as illustrated. The said ends 5 2 and 3 are secured in their proper positions to the main shell of the tank or boiler 1 by means of the rivets 5 at the front and the rivets 6 at the rear; but of course it will be understood that these various parts may be assembled 10 and secured together in any other suitable and well-known manner. Suitably secured within the said tank or boiler at the rear end thereof, so as to rest against the inner surface of the said rear end plate 3, is a gasket-like device 7, made of a suitable flexible material, preferably rubber, the same being provided with a centrally-arranged opening 8, which opening is of a smaller diameter than the opening 4 in the said end plate 3, as will be 15 clearly seen from an inspection of Fig. 3 of the drawings. Within the said tank or boiler 1, at or near the front end of the same, is suitably secured a funnel-shaped fluid-mixture-receiving device 9, which is made with the 20 large open part 10 and the smaller open part or throat 11, substantially as illustrated in Fig. 3 of the drawings. Within this throat 11 I have secured, preferably by means of rivets 13 or in any other suitable manner, the closed 25 end portion of a receiving or holding thimble 12. This thimble 12 is made with an outwardly-flaring receiving end 14 and is provided with any desired number of longitudinally-extending slits 16, so as to provide suitable spring-leaves 15 for suitably receiving and holding the end 19 of a log or beam 18 in position for treatment in the manner to be 30 hereinafter more fully described. The inner and closed end of this thimble 12 is provided 35 with any desired number and suitably-disposed perforations or holes 17, as clearly illustrated. The said tank or boiler 1 may be supported upon suitably-arranged and suitably-constructed standards 20 and 21, as here- 40 in shown, or any other means of support for the boiler may be employed, as will be clearly understood.

Leading into the front end plate 2 of the tank or boiler 1 is a pipe 22 and a valve 23 45 therein for conducting the fluid mixture with which the wood is to be impregnated into the chamber 24, formed by the inner walls of the funnel-shaped device 9, the perforated end of the thimble 12, and the inner surface of the 50 end plate 2 of the boiler, as shown more particularly in Fig. 3 of the drawings, and 55 is a pipe provided with a valve 26 for conducting steam into the said chamber 24, and thereby maintaining the fluid mixture in said 55 chamber under pressure while forcing said mixture through the perforations 17 of the thimble 12 into the supported end of the log or beam 18. A pressure indicator or gage 27 and a safety-valve or blow-off 28, both of 60 any suitable and well-known constructions, may be used with the tank or boiler 1, the same being preferably connected with the

front end plate 2, as herein shown. In longitudinal alinement with the said tank or boiler 1 may be placed a track or rails 29, on 70 which is movably arranged a suitably-constructed car 30, provided with a suitably-constructed centering and holding device 31. A suitable lifting-jack 32 may be employed for lifting the log or beam to be treated in its 75 proper position in front of the opening 4 in the rear end 3 of the tank or boiler 1, the said jack also being employed for supporting the one end portion of the log or beam when the latter has been passed into and through the 80 said opening 4 in the end 3 and has its end 19 supported in the thimble 12 for treatment, the lifting-jack 32 thus serving to remove any undue strain from the end 3 of the boiler or tank 1 and also from the said thimble 12, 85 as will be clearly evident. When the log or beam 18 has been inserted in its proper position within the boiler or tank 1 for treatment, as shown in the several figures of the drawings, then the car 30 and its centering 90 or holding device 31 are pushed directly against the free end 33 of the log or beam 18 and a pawl 34, which is connected with the carriage or car 30, made to engage one of the teeth of a suitably-disposed toothed rack 35, 95 connected with one or both of the rails 29. The purpose of this rack and pawl is that when great pressure is brought to bear directly against the end 19 of the log or beam 18 during the process of treating the wood 100 the said car will be held in a fixed and stationary position, its centering or holding device 31 acting as a stop, and thereby preventing the log or beam from being forced from its proper position in the thimble 12 during 105 the process of impregnation of the wood with the mixture. Of course it will be clearly understood that in place of the car and the ratchet mechanism hereinabove mentioned, and illustrated in the drawings, any other 110 holding means may be employed for retaining the log or beam in its position within the tank or boiler 1 during the process of impregnation.

To prevent the car from accidentally being brought against the end plate 3 of the tank 115 or boiler when there is no log or beam in position, the said tank or boiler may be provided with a pair of rearwardly-extending arms or brackets 36, formed with receiving-sockets 37, in which are slidably arranged 120 upon a pin 38 in each socket a spring-actuated and slotted buffer 39, as clearly illustrated in Fig. 6 of the drawings.

Having described the construction of the apparatus and the various arrangements of 125 the parts thereof for the reception of a log or beam of wood, I will now briefly set forth its use and operations for rendering the wood resistible or tenacious to pressure from a die or dies without distorting or tearing the fiber 130 or for rendering the wood fireproof or impervious to moisture after having been impregnated with the mixture or fluid to which the log or beam is to be treated.

The log or beam 18 in its green state is inserted into and passed through the opening 4 in the end plate 3 of the tank or boiler 1, so that its inner end 19 will rest quite close to the perforated end piece of the thimble 12, as illustrated in the dotted outline in Fig. 3 of the drawings, the said spring-leaves 15 of the thimble 12 serving to grasp the end of the log, and thereby hold it in its centered and supporting position within said thimble and near the throat of the funnel-shaped device 9. At the same time the inner marginal edge which surrounds the opening 8 in the said gasket-like device 7 will arrange itself closely around the outer surface of the inserted log or beam, as represented more particularly in said Fig. 2^A of the drawings, thereby providing a perfect closure around the log or beam and preventing the escape of steam and fumes that may have escaped from the funnel-shaped device 9 into the main body of the tank or boiler 1. Having in this manner arranged the log or beam in its proper position to be treated, the valve 23 in the pipe 22 is opened and the fluid mixture is admitted into the chamber 24. The valve 26 in the steam-conveying pipe 25 is next opened and steam admitted into the chamber 24, thereby bringing the fluid mixture with which the wood is to be impregnated under great pressure. The action of the fluid mixture, with the pressure back of it, is such that it will be forced through the holes or perforations 17 of the thimble 12 and will pass directly into the end 19 of the log or beam 18, the fluid mixture following the long grain of the wood and passing longitudinally through the wood, thereby thoroughly impregnating the log or beam with the fluid mixture, which renders the wood after the mixture has dried very hard and tenacious.

The fluid mixture usually employed for the treatment of the log or beam is a mixture usually consisting of water and a tough cementitious matter, such as glue, or a mixture consisting of water, bichromate of potash, and mica, or of water, formic aldehyde, and gelatin, either with or without mica, with an addition thereto of xyline and sulfoborate of ammonia. Of course it will also be evident that the apparatus may be employed for fire-proofing or waterproofing wood in a similar manner to that hereinabove set forth and also for impregnating the log or beam or other material with filler compounds of the various kinds.

I am aware that various changes may be made in the several arrangements and combinations of the devices and parts composed in my novel apparatus for impregnating wood without departing from the scope of my present invention. Hence I do not limit my invention to the exact arrangements and combinations of the devices and parts as herein described and as illustrated in the accompanying drawings, nor do I confine myself to

the details of the construction of the various parts.

Having thus described my invention, what I claim is—

1. In an apparatus for the impregnation of wood, for the purposes of rendering it tenacious and resistible to pressure, or for fire-proofing or waterproofing the same, the combination, with means for supporting a log or beam which is to be impregnated, of means for forcing the impregnating mixture longitudinally through the said log or beam, consisting, essentially, of a funnel-shaped mixture-receiving device, having an outwardly flaring and expansible delivery-throat into which a portion of the logs of different thicknesses may be placed, so that said throat encompasses said portion of the log and helps support the same, substantially as and for the purposes set forth.

2. In an apparatus for the impregnation of wood, for the purposes of rendering it tenacious and resistible to pressure, or for fire-proofing or waterproofing the same, the combination, with means for supporting a log or beam which is to be impregnated, of means for forcing the impregnating mixture into one end of the log or beam, consisting, essentially, of a funnel-shaped mixture-receiving device, having a mixture-chamber provided with a delivery-throat, and a perforated thimble having an expansible holding portion in which the one end of the log or beam is placed and held, the perforated portion of said thimble forming a part of the mixture-chamber and being arranged directly within the said delivery-throat, substantially as and for the purposes set forth.

3. In an apparatus for the impregnation of wood, for the purposes of rendering it tenacious and resistible to pressure, or for fire-proofing or waterproofing the same, the combination, with means for supporting a log or beam which is to be impregnated, of means for forcing the impregnating mixture into one end of the log or beam and distributing said mixture longitudinally through said log or beam, consisting, essentially, of a funnel-shaped mixture-receiving device, having a delivery-throat, a perforated thimble in which the one end of the log or beam is placed, and spring-plates forming a part of said thimble for holding the end of the log or beam in place, substantially as and for the purposes set forth.

4. In an apparatus for the impregnation of wood, for the purposes of rendering it tenacious and resistible to pressure, or for fire-proofing or waterproofing the same, the combination, with means for supporting a log or beam which is to be impregnated, of means for forcing the impregnating mixture into one end of the log or beam and distributing said mixture longitudinally through the said log or beam, a car, a centering or holding device connected with said car, adapted to be brought

against the opposite end of said log or beam, and means for locking said car in a fixed position, substantially as and for the purposes set forth.

5. In an apparatus for the impregnation of wood, for the purposes of rendering it tenacious and resistible to pressure, or for fire-proofing or waterproofing the same, the combination, with means for supporting a log or beam which is to be impregnated, of means for forcing the impregnating mixture into one end of the log or beam and distributing said mixture longitudinally through the said log or beam, consisting, essentially, of a funnel-shaped mixture-receiving device, having a delivery-throat in front of which the one end of the log or beam is placed, a car, a centering or holding device connected with said car, adapted to be brought against the opposite end of said log or beam, and means for locking said car in a fixed position, substantially as and for the purposes set forth.

6. In an apparatus for the impregnation of wood, for the purposes of rendering it tenacious and resistible to pressure, or for fire-proofing or waterproofing the same, the combination, with means for supporting a log or beam which is to be impregnated, of means for forcing the impregnating mixture into one end of the log or beam and distributing said mixture longitudinally through said log or beam, consisting, essentially, of a funnel-shaped mixture-receiving device, having a delivery-throat, and a perforated thimble in which the one end of the log or beam is placed and held, a car, a centering or holding device connected with said car, adapted to be brought against the opposite end of said log or beam, and means for locking said car in a fixed position, substantially as and for the purposes set forth.

7. In an apparatus for the impregnation of wood, for the purposes of rendering it tenacious and resistible to pressure, or for fire-proofing or waterproofing the same, the combination, with means for supporting a log or beam which is to be impregnated, of means for forcing the impregnating mixture into one end of the log or beam and distributing said mixture longitudinally through said log or beam, consisting, essentially, of a funnel-shaped mixture-receiving device, having a delivery-throat, a perforated thimble in which the one end of the log or beam is placed, and spring-plates forming a part of said thimble for holding the end of the log or beam in place, a car, a centering or holding device connected with said car, adapted to be brought against the opposite end of said log or beam, and means for locking said car in a fixed position, substantially as and for the purposes set forth.

8. An apparatus for the impregnation of wood, for the purposes of rendering it tenacious and resistible to pressure, or for fire-proofing or waterproofing the same, comprising, a tank or boiler having a closed end plate and an end plate provided with a log-receiving opening, and means within said tank or boiler for supporting the one end of said log and forcing a fluid impregnating mixture into said supported end of the log and distributing said mixture longitudinally through the said log, substantially as and for the purposes set forth.

9. An apparatus for the impregnation of wood, for the purposes of rendering it tenacious and resistible to pressure, or for fire-proofing or waterproofing the same, comprising, a tank or boiler having a closed end plate and an end plate provided with a log-receiving opening, and means within said tank or boiler for supporting the one end of said log and forcing a fluid impregnating mixture into said supported end of the log and distributing said mixture longitudinally through the said log, substantially as and for the purposes set forth.

10. An apparatus for the impregnation of wood, for the purposes of rendering it tenacious and resistible to pressure, or for fire-proofing or waterproofing the same, comprising, a tank or boiler having a closed end plate and an end plate provided with a log-receiving opening, and means within said tank or boiler for supporting the one end of said log and forcing a fluid impregnating mixture into said supported end of the log and distributing said mixture longitudinally through the said log, consisting, essentially, of a funnel-shaped mixture-receiving device, having a delivery-throat in front of which the one end of the log is placed, substantially as and for the purposes set forth.

11. An apparatus for the impregnation of wood, for the purposes of rendering it tenacious and resistible to pressure, or for fire-proofing or waterproofing the same, comprising, a tank or boiler having a closed end plate and an end plate provided with a log-receiving opening, and means within said tank or boiler for supporting the one end of said log and forcing a fluid impregnating mixture into said supported end of the log and distributing said mixture longitudinally through the said log, consisting, essentially, of a funnel-shaped mixture-receiving device having a delivery-throat, and a perforated thimble in which the one end of the log is placed, substantially as and for the purposes set forth.

12. An apparatus for the impregnation of wood, for the purposes of rendering it tenacious and resistible to pressure, or for fire-proofing or waterproofing the same, comprising, a tank or boiler having a closed end plate and an end plate provided with a log-receiving opening, and means within said tank or boiler for supporting the one end of said log and forcing a fluid impregnating mixture into said supported end of the log and distributing said mixture longitudinally through the said log, consisting, essentially, of a funnel-shaped mixture-receiving device having a delivery-throat, a perforated thimble in which the one end of the log is placed, and spring-plates forming a part of said thimble for holding the end of the log in place, substantially as and for the purposes set forth.

13. An apparatus for the impregnation of wood, for the purposes of rendering it tenacious and resistible to pressure, or for fire-proofing or waterproofing the same, comprising, a tank or boiler having a closed end plate and an end plate provided with a log-receiving opening, and means within said tank or boiler for supporting the one end of said log and forcing a fluid impregnating mixture into said supported end of the log and dis-

tributing said mixture longitudinally through the said log, a car, a centering or holding device connected with said car, adapted to be brought against the opposite end of said log, 5 and means for locking said car in a fixed position, substantially as and for the purposes set forth.

13. An apparatus for the impregnation of wood, for the purposes of rendering it tenacious and resistible to pressure, or for fire-proofing or waterproofing the same, comprising, a tank or boiler having a closed end plate and an end plate provided with a log-receiving opening, and means within said 15 tank or boiler for supporting the one end of said log and forcing a fluid impregnating mixture into said supported end of the log and distributing said mixture longitudinally through the said log, consisting, essentially, 20 of a funnel-shaped mixture-receiving device, having a delivery-throat in front of which the one end of the log is placed, a car, a centering or holding device connected with said car, adapted to be brought against the opposite 25 end of said log, and means for locking said car in a fixed position, substantially as and for the purposes set forth.

14. An apparatus for the impregnation of wood, for the purposes of rendering it tenacious and resistible to pressure, or for fire-proofing or waterproofing the same, comprising, a tank or boiler having a closed end plate and an end plate provided with a log-receiving opening, and means within said 35 tank or boiler for supporting the one end of said log and forcing a fluid impregnating mixture into said supported end of the log and distributing said mixture longitudinally through the said log, consisting, essentially, 40 of a funnel-shaped mixture-receiving device having a delivery-throat, and a perforated thimble in which the one end of the log is placed, a car, a centering or holding device connected with said car, adapted to be brought 45 against the opposite end of said log, and means for locking said car in a fixed position, substantially as and for the purposes set forth.

15. An apparatus for the impregnation of wood, for the purposes of rendering it tenacious and resistible to pressure, or for fire-proofing or waterproofing the same, comprising, a tank or boiler having a closed end plate and an end plate provided with a log-receiving opening, and means within said 55 tank or boiler for supporting the one end of said log and forcing a fluid impregnating mixture into said supported end of the log and distributing said mixture longitudinally through the said log, consisting, essentially, 60 of a funnel-shaped mixture-receiving device having a delivery-throat, a perforated thimble in which the one end of the log is placed, and spring-plates forming a part of said thimble for holding the end of the log in place, a 65 car, a centering or holding device connected with said car, adapted to be brought against

the opposite end of said log, and means for locking said car in a fixed position, substantially as and for the purposes set forth.

16. An apparatus for the impregnation of wood, for the purposes of rendering it tenacious and resistible to pressure, or for fire-proofing or waterproofing the same, comprising, a tank or boiler having a closed end plate and an end plate provided with a log-receiving opening, a flexible gasket-like device provided with a central opening arranged against the inner surface of said open end plate, and means within said tank or boiler for supporting the one end of said log and forcing a fluid impregnating mixture into said supported end of the log and distributing said mixture longitudinally through the said log, substantially as and for the purposes set forth. 70 75 80 85

17. An apparatus for the impregnation of wood, for the purposes of rendering it tenacious and resistible to pressure, or for fire-proofing or waterproofing the same, comprising, a tank or boiler having a closed end plate and an end plate provided with a log-receiving opening, a flexible gasket-like device provided with a central opening arranged against the inner surface of said open end plate, and means within said tank or boiler for supporting the one end of said log and forcing a fluid impregnating mixture into said supported end of the log and distributing said mixture longitudinally through the said log, consisting, essentially, of a funnel-shaped mixture-receiving device, having a delivery-throat in front of which the one end of the log is placed, substantially as and for the purposes set forth. 90 95 100

18. An apparatus for the impregnation of wood, for the purposes of rendering it tenacious and resistible to pressure, or for fire-proofing or waterproofing the same, comprising, a tank or boiler having a closed end plate and an end plate provided with a log-receiving opening, a flexible gasket-like device provided with a central opening arranged against the inner surface of said open end plate, and means within said tank or boiler for supporting the one end of said log and forcing a fluid impregnating mixture into said supported end of the log and distributing said mixture longitudinally through the said log, consisting, essentially, of a funnel-shaped mixture-receiving device having a delivery-throat, and a perforated thimble in which the one end of the log is placed, substantially as and for the purposes set forth. 105 110 115 120

19. An apparatus for the impregnation of wood, for the purposes of rendering it tenacious and resistible to pressure, or for fire-proofing or waterproofing the same, comprising, a tank or boiler having a closed end plate and an end plate provided with a log-receiving opening, a flexible gasket-like device provided with a central opening arranged against the inner surface of said open end plate, and means within said tank or boiler for support- 125 130

ing the one end of said log and forcing a fluid impregnating mixture into said supported end of the log and distributing said mixture longitudinally through the said log, consisting, essentially, of a funnel-shaped mixture-receiving device having a delivery-throat, a perforated thimble in which the one end of the log is placed, and spring-plates forming a part of said thimble for holding the end of

the log in place, substantially as and for the 10 purposes set forth.

In testimony that I claim the invention set forth above I have hereunto set my hand this 18th day of December, 1901.

JOHN BORNER.
